UNITED STATES PATENT OFFICE.

RALPH R. BOYLES, OF ST. PAUL, MINNESOTA, ASSIGNOR TO AMERICAN ALUMINUM
WARE CO., A CORPORATION OF NEW JERSEY.

SINK STRAINER.

Application filed September 23, 1922. Serial No. 590,041.

To all whom it may concern:

Be it known that I, RALPH R. BOYLES, a citizen of the United States, residing at St. Paul, in the county of Ramsey and State 5 of Minnesota, have invented a new and useful Sink Strainer, of which the following is a specification.

My invention relates to improvements in sink strainers.

10 The present sink strainers in general domestic use are slow to drain and occasion considerable inconvenience, due to the drippings which fall therefrom during the act of emptying the same.

15 It is the object of this invention to provide an improved receptacle for kitchen refuse adapted to drain freely in horizontal receiving position and to trap the retained liquid waste when tilted from the horizontal. It will be understood that a strainer of 20 this type is set removably, usually in the corner of the sink, at a convenient height for water containing potato peelings or other 25 solid matter to be poured through the strainer so that the liquid will run away through the sink drain and the solid matter remain in the strainer. Subsequently the strainer is lifted out of its place and its contents dumped into the garbage pail, but in 30 doing this a trail of liquid is usually left across the kitchen floor, since draining goes on for some time. The purpose of my invention is to enable the portable strainer to be tilted after it has been taken from its place, so that liquid will not continue to 35 drain from it and will be kept from dripping onto the floor as the strainer is carried to its dumping place.

40 With the foregoing and other objects in view, which will appear in the following description, the invention resides in the novel combination and arrangement of parts and in the details of construction hereinafter described and claimed.

45 In the drawings, Fig. 1 is a perspective view of a strainer embodying my invention; Figs. 2 and 3 are longitudinal, sectional views thereof, the former illustrating the strainer in receiving draining position, while the latter illustrates said strainer tilted from the horizontal and in position to trap the drip therefrom and Fig. 4 is a plan view of 50 a strainer showing an alternate form of my invention.

Having reference to the drawings, it will 55 be observed that my improved strainer comprises a bottom A, two sidewalls 10 and an outwardly bowed endwall 11 forming a three cornered receptacle for waste. The sidewalls 10 for a ninety degree angle and fit 60 snugly against the sides of a sink in a corner thereof. The structure is preferably stamped from a single piece of sheet metal, the walls being slightly rounded at their junctions as 65 shown and the upper margins thereof beaded as at 12 to enhance the appearance of the article and increase its strength.

Draining portions 13, in the bottom, reaching through adjoining parallel areas thereof are offset at their adjacent margins, the 70 spaces between said margins being spanned by webs 14 having discharge openings 15 therein. Said draining portions 13 rest in similarly inclined relation, when the strainer is in horizontal, waste receiving position 75 (Fig. 2) and direct the drip from the receptacle through said discharge openings 15. The draining portion 13 adjacent the endwall 11 merges into the same and together with said endwall and the adjacent section 80 of the sidewalls 10 forms a pocket or trap B into which the retained liquid waste is drained upon tilting the strainer end downward, as shown in Fig. 3. In this position, the draining portions 13 slope downward 85 toward the pocket B, the drip flowing from one portion 13 to the next and finally lodging in said pocket. The draining of liquid waste over said portions 13 and into the 90 pocket B simulates the flow of water from one shingle to another in its passage down a shingled roof and into gutters at the eaves. From the foregoing it will be understood 95 that my improved strainer will function rapidly in horizontal, receiving position and that the discharge therefrom of any retained liquid waste may be avoided, in moving the strainer, by tilting the same and thereby trapping the drip therein.

In addition to the preferred embodiment 100 of my invention illustrated in Figs. 1, 2 and 3, I contemplate the use of alternate forms thereof. For example and as shown in Fig. 4, the draining portions 13 may be curved to approximate the curvature of the endwall 11. In this form, the strainer can be dipped sidewise considerably without spilling the 105 trapped liquid waste from the bottom there-

of. I also contemplate omitting the webs 14 in another form, thereby increasing the draining capacity of the strainer.

Further changes in the specific forms of my invention, as herein disclosed, may be made within the scope of what is claimed without departing from the spirit of my invention.

Having described my invention, what I claim as new and desire to protect by Letters Patent is:

1. A portable strainer adapted to stand in horizontal position for draining its contents and to be tilted into inclined position for conveying the residue to a dumping place, said strainer comprising side walls for confining its contents against lateral escape in any direction, and a bottom which is provided with impervious draining portions inclined in one direction when the strainer is in normal horizontal position and in the opposite direction when the strainer is tilted, said bottom having an outlet between the adjacent edges of each two of said draining portions and said edges overlapping enough for one portion to receive drainage from the other when the strainer is tilted.

2. A removable triangular strainer for the corner of a sink, having side walls for its entire periphery and a bottom which is

provided with parallel draining portions inclined toward the small end of the strainer when the strainer is in normal position and in the opposite direction when the strainer is tilted, said bottom having an outlet between the adjacent edges of each two of said draining portions and said edges being in such relation to each other that one portion drains onto the other when the strainer is tilted.

3. A removable triangular strainer for the corner of a sink, having side walls for its entire periphery and a bottom which is provided with draining portions inclined toward the small end of the strainer when the strainer is in normal position and in the opposite direction when the strainer is tilted, said bottom having an outlet between the adjacent edges of each two of said draining portions and said edges being in such relation to each other that one portion drains onto the other when the strainer is tilted, said straining portions being curved concavely with respect to the small end of the strainer, whereby in tilted position of the strainer the ends of the outlet between any two draining portions are higher than its middle.

In testimony whereof, I have signed my name to this specification.

RALPH R. BOYLES.
